COSMETIC CONTAINER

Jacques Kreisler, New Rochelle, N. Y.

Application April 16, 1935, Serial No. 16,574

19 Claims. (Cl. 206—56)

The present invention relates to cosmetic containers and, more particularly, to lipstick holders and covers therefor.

One object of the invention is to provide a lipstick container which is substantially dust proof.

Another object of the invention is to provide a lipstick holder with a permanently attached cover constructed and arranged to be conveniently and readily opened and closed.

A further object of the invention is to provide a lipstick holder and cover constituting a case so arranged and constructed that the lipstick holder can be projected therefrom by the convenient manipulation of a button or finger piece on said case by the hand in which the case is held.

A further object of the invention is to provide a lipstick container with a mirror so disposed and arranged therein that the user may observe her lips while she applies the lipstick.

A yet further object is generally to improve the construction of lipstick containers.

The above objects of the invention and other objects ancillary thereto will best be understood from the following description considered in connection with the accompanying drawing.

In the drawing:

Fig. 1 is a perspective view of the lipstick container embodying the present invention;

Fig. 2 is a sectional view on the line 2—2 of Fig. 1;

Fig. 3 is a plan view of the lipstick container in open condition and showing the lipstick projected from the holder;

Fig. 4 is an enlarged sectional view on the line 4—4 of Fig. 2;

Fig. 5 is a fragmentary exploded plan view of the free end portion of the cover element of the container and the parts carried thereby;

Fig. 6 is a view similar to Fig. 5 in side elevation;

Fig. 7 is a top plan view showing a modification of the spring-catch.

Fig. 8 is a plan view of the cover showing a modification;

Fig. 9 is a sectional view on the line 9—9 of Fig. 8.

The improved lipstick container of the present invention comprises a lipstick holder 10 and a cover 12 therefor hinged together at their ends by a spring hinge 15 which biases the holder and cover for relative movement away from each other about the hinge 15 as a pivot to the open condition illustrated in Fig. 3. Said holder

and cover are releasably retained in closed position; as illustrated in Figs. 1 and 2, by a spring catch which is released by operation of the finger-piece 14.

The holder 10 and the cover 12 constitutes a protective case for the lipstick 16 carried by said holder and are constructed and arranged to effectively prevent the entrance of dust and other foreign particles into the holder 10 and into the case. For this purpose provision is made for covering the slot 18 through which the finger-piece 20 on the lipstick carrier 22 extends for projecting and retracting the lipstick 16. Thus, as here shown, the holder 10 and cover 12 are arranged so that when the cover 12 is closed it is positioned adjacent to and overlies the inner wall 11 which is provided with said slot 18. Also for the same purpose, the cover and holder are constructed and arranged to releasably close together in sealing relation to cover the open end 20 of the holder 10 through which the lipstick 16 is projected and retracted and to eliminate any openings through which dust or foreign matter can pass into the case. The holder and cover are also so constructed and so related to each other as to permit the holder to move freely away from the cover in response to the force of the spring 17 of the hinge 15 when the spring catch hereinafter described is released by depressing the finger-piece 14. These results are accomplished in the present embodiment of the invention by the construction and arrangement which will now be described in greater detail.

The holder 10 comprises the inner curved wall 11 and an outer curved wall 13 which is somewhat wider than said inner wall whereby the latter is offset inwardly, thus forming longitudinally extending shoulders 30 which, as will presently appear, constitute sealing edges when the cover is closed. The cover 12 comprises a curved wall 32 which, for a portion of its length, is substantially equal to the length of the holder 10, is of the same width as the wall 13 of said holder, and in said portion terminates in free longitudinal edges 34 which engage the shoulders 30 and together therewith constitute means to seal the case against the entrance of dust and other foreign particles. The outer or free end of said cover comprises a closed peripheral wall portion 36 offset inwardly from the wall 32 forming a shoulder 38 coextensive with the peripheral extent of the wall 32. Said wall portion 36 which extends beyond the edges 34 of the wall 32 is provided with a slot 40 closed at its inner end and open at its outer end. As best shown in Figs. 5

and 6, the portions of the wall 36 which define said slot have longitudinal extensions 39.

A sleeve 42 having an inner wall 44 fits within said wall 36 and is provided with an opening 46, which registers with said slot 40, and stop members 48 which engage the free edge of the wall portion 36 adjacent to the extensions 39. The sleeve 42 is held in position on the wall 36 by a cap 50 which engages the outer periphery of the wall 36 and is positioned inwardly thereof by engagement with the shoulder 38. Said cap 50 has an opening 52 which registers with the slot 40 in the wall 36 and with the opening 46 in the sleeve 42 to permit movement of the finger piece 14. Said cap may be secured in position in any suitable way preferably by engagement of the inner side walls of the cap with the dots 54 on the outer side of the wall 36.

The catch 68 for securing the lipstick holder 10 in closed position against the force of the spring 15 is arranged to engage the adjacent inner surface of the wall 11 when the holder is closed. Said catch is projected and retracted through an opening 62 in the wall 44 of the sleeve 42 under the control of an S-shaped spring 64 one end of which is fixed to the catch and the other end of which is fixed to the sleeve 42 in any suitable way such as by a rivet 66 or, as illustrated in Fig. 7, by ears 68 passed through small opening 69 in the sleeve 42 and reflexed laterally of said openings. Said spring 64 carries the finger piece 14. The operation of the spring catch thus constituted is readily apparent and it will be noticed that when the finger piece 14 is depressed the end thereof, which is fixed to the catch element 60 moves toward the open end of the sleeve 42 and carries therewith the catch element 68 out of engagement with the wall 11 of the lipstick holder.

It will be observed that when the lipstick holder is closed the open end thereof lies closely adjacent the wall 44 and is closed thereby, that the edges 30 and 34 are in engagement, and that the free edge 70 of the wall 13 engages the inner edge of the cap 50, thus effectively sealing the lipstick holder 10 and the case constituted thereby and by the cover 12 against the entrance of dust and other foreign particles. To permit the end 72 of the wall 11 to clear the cap 50 and wall 44 in the movement of the holder 10 to open and closed positions, said wall 11 terminates at said end 72 somewhat short of the end 70 of the wall 13. It will be noticed also that the wall 36 and cap 50 project a substantial distance beyond the wall portion 32 into which the holder 10 is rested in closed position. Hence said wall 36 and cap 50 constitute a handle by which the case may be held in one hand while the button or finger piece 14 is depressed by a finger of the same hand to permit the spring 15 to project the holder out of the case.

The lipstick container may be provided with a mirror. Accordingly, as shown in Figs. 8 and 9, the wall 32a of the cover 12 which is otherwise of the same construction as the wall 32 is provided with a longitudinal depression 80 within which a mirror 82 is disposed preferably flush with the inner surface of the wall 32a. With this arrangement of the mirror it is possible to dispose the cover at such an angle that the user can observe her lips while applying the lipstick to them. This can be accomplished by holding the cover and lipstick holder at about right angles to each other with the cover extending in a direction approximately parallel to the lips.

75 Thus it is seen that the constructions herein

shown and described are well adapted to accomplish the several objects of the present invention. It will be understood, however, that certain changes may be made therein without departing from the dominant idea of the invention. Therefore, I do not wish to be limited to the precise constructions herein disclosed except as may be required by the appended claims and the prior art.

5

What is claimed as new and useful is:

1. A lipstick container comprising a lipstick holder having a closed end and an open end through which the lipstick can be projected and retracted, a cover hinged at one end to said closed end of the holder whereby said cover and holder are foldably related and having an end portion 15 overlying said open end of the holder when the cover and holder are folded together, said overlying end portion projecting a substantial distance beyond said open end of the holder in folded relation, and a catch movably mounted on said 20 projecting end portion of the cover for releasable engagement with the open end portion of said holder to releasably secure said cover and holder in said folded relation.

2. A lipstick container comprising two members 25 swingably hinged together in foldable relation, one of said members comprising a lipstick holder provided with an open end through which the lipstick can be projected and retracted, the other member comprising a wall extending from said 30 hinge longitudinally of said holder beyond the open end of the holder when said members are in folded relation, and a wall portion extending from the end of said other member opposite said hinge to the edge of the open end of said holder 35 when said members are folded, and means for releasably securing said members in folded relation.

3. A lipstick container comprising a lipstick holder having a closed end and an open end 40 through which the lipstick can be projected and retracted, a cover hinged at one end to said closed end of the holder whereby said cover and holder are foldably related and having an end portion overlying said open end of the holder when the 45 cover and holder are folded together, said overlying end portion comprising a finger grip projecting a substantial distance beyond said open end of the holder in folded relation, and a catch movably mounted on said projecting end portion of 50 the cover for releasable engagement with the open end portion of said holder to releasably secure said cover and holder in said folded relation, and means for biasing said holder to move away from said cover on said hinge when said catch 55 is released.

4. A lipstick container comprising two members swingably hinged together in foldable relation, one of said members comprising a lipstick holder provided with an open end through which the 60 lipstick can be projected and retracted, said holder having a carrier for the lipstick and a slotted wall through which a finger piece for operating said carrier projects, the other member comprising a wall extending from said hinge 65 longitudinally of said holder beyond the open end of the holder and overlying said slotted wall when said members are in folded relation, and a wall portion extending from the end of said other member opposite said hinge to the open 70 end of said holder when said members are folded, means mounted in the portion of said other member which extends beyond the open end of said holder for releasably securing said members in folded relation, means for biasing said holder to 75

move away from said other member, and releasable means for holding said members in folded relation.

5. A container comprising a receptacle open at one end, a member hinged adjacent the opposite end of said receptacle in foldable relation thereto, said receptacle having a carrier movably mounted therein and a slotted wall through which there projects a finger piece for moving said carrier, said member extending longitudinally of and overlying said slotted wall of said receptacle when the member and receptacle are folded together, said member and receptacle having longitudinally extending edges which engage each other when 10 said receptacle and member are folded together, and means for closing the open end of said receptacle.

6. A container comprising a receptacle open at one end, said container having an inwardly offset wall portion forming longitudinally extending shoulders, and a member hinged adjacent the opposite end of said receptacle extending longitudinally of said receptacle and having a portion overlying said open end of the receptacle when 20 said member and receptacle are folded together and having longitudinally extending side edges which engage said shoulders when said receptacle and member are folded together.

7. A container comprising a receptacle open at one end, said container having an inwardly offset wall portion forming longitudinally extending shoulders, a member hinged adjacent the opposite end of said receptacle in foldable relation thereto, said member extending longitudinally of and overlying a longitudinally extending peripheral wall portion of said receptacle when the member and receptacle are folded together and having longitudinally extending edges which engage said shoulders when said receptacle and member are folded together, and said member having a portion which projects beyond the edges thereof and overlies said open end of the receptacle when said receptacle and member are folded together, means biasing said member and receptacle to unfolded relation, and means for releasably holding said receptacle and member in folded relation.

8. A lipstick container comprising a lipstick holder having a closed end and an open end and a wall having a longitudinally extending slot, a lipstick projector and retractor within said holder and having a projection extending through said slot whereby the lipstick can be projected and retracted with respect to said open end of the holder, a cover having one end hinged to said closed end of the holder, a wall overlying said slotted wall of the holder when the holder and cover are in folded relation, an end portion overlying said open end of the holder when the holder and cover are in folded relation, and a catch movably mounted adjacent said overlying end portion of the cover for releasably engaging the open end portion of said holder to releasably secure the holder and cover in folded relation.

9. A lipstick container comprising a lipstick holder having a closed end and an open end and a wall having a longitudinally extending slot, a lipstick projector and retractor within said holder and having a projection extending through said slot whereby the lipstick can be projected and retracted with respect to said open end of the holder, a cover having one end hinged directly to said closed end of the holder, a wall overlying 75 said slotted wall of the holder when the holder

and cover are in folded relation, an end portion overlying said open end of the holder when the holder and cover are in folded relation, and a catch movably mounted adjacent said overlying end portion of the cover for releasably engaging the open end portion of said holder to releasably secure the holder and cover in folded relation and spring means for moving said holder and cover to at least partially unfolded relation when said catch is released.

10. A lipstick container comprising a tubular member open at one end and closed at its other end, a cover hinged at one end to the closed end of said tubular member whereby said cover and member are foldably related, means forming a housing at the other end of said cover, said housing having a wall spaced inwardly of one end of the housing and provided with an opening, spring means biasing said cover to unfolded relation, a catch mounted in said housing in movable relation thereto through said opening for releasable engagement with the open end of said member when the latter and said cover are folded together, and a spring in said housing biasing said catch for engagement with said member.

11. A lipstick container comprising a tubular member open at one end and closed at its other end, a cover member having a wall portion overlying a wall portion of said tubular member and hinged to the other end of the latter whereby said members are foldably related and a wall portion overlying said open end of the tubular member, said cover member having a catch disposed adjacent the free end thereof in position to engage the open end of said tubular member at the wall portion thereof which is adjacent to said first mentioned wall portion of the cover member when said members are folded together.

12. A container comprising a receptacle member and a cover member hinged together, one of said members having a housing, a catch movable in said housing for releasable engagement with the other member, an S-shaped spring fixed at one end to said catch and at its other end to said housing, and arranged to project said catch for engagement with said other member, and means for compressing said spring to thereby move said catch out of engagement with said other member.

13. A container comprising a receptacle member and a cover member hinged together, one of said members having two walls disposed substantially at right angles to each other, each of said walls having an opening therein, a catch movable in the opening in one of said walls for releasable engagement with the other member, an S-shaped spring fixed at one end to said catch and at its other end to said other wall, and a finger piece movable in the opening in said latter wall for compressing said spring to thereby move said catch out of engagement with said other member.

14. A container comprising a receptacle member closed at one end and open at its other end, said receptacle having a carrier movably mounted therein and a slotted wall through which there projects a finger piece for moving said carrier, a cover member pivotally connected to said receptacle at said closed end on a hinge disposed substantially medially between the opposite sides of the receptacle whereby said receptacle and cover are foldably related with the receptacle in nested relation when said members are folded together on said hinge, said receptacle having longitudinally extending medial edges in the plane of said hinge, and said cover member having lon- 75

gitudinally extending edges which engage said medial edges of the receptacle member when said members are folded together in nested relation.

- 5 15. A container comprising a receptacle member closed at one end and open at its other end, a cover member pivotally connected to said receptacle at said closed end on a hinge disposed substantially medially between the opposite sides 10 of the receptacle whereby said receptacle and cover are foldably related with the receptacle in nested relation when said members are folded together on said hinge, said receptacle having longitudinally extending medial edges in the 15 plane of said hinge, and said cover member having longitudinally extending edges which engage said medial edges of the receptacle member when said members are folded together in nested relation, said cover member having a portion projecting beyond the longitudinally extending edges thereof closely adjacent to said open end of the receptacle when said members are folded together, the portion of said receptacle at one side 20 of said medial edges adjacent the cover member being sufficiently shorter than the other side of said receptacle member whereby to permit said open end to clear said projecting portion in the movement of said receptacle to folded and unfolded relation with respect to said cover member. 25
16. A container comprising a receptacle open at one end, a member hinged adjacent the opposite end of said receptacle in foldable relation thereto, said member having a wall portion extending longitudinally of and overlying a longitudinally extending peripheral wall portion of said receptacle when the member and receptacle are folded together, said member also having an end wall portion projecting beyond the open end of 30 said receptacle when the latter and said member are folded together, said last mentioned wall portion having an open end, and a cap mounted on said last mentioned wall portion and closing the open end thereof. 35
- 40 45 17. A container comprising a receptacle open at one end, a member hinged adjacent the opposite end of said receptacle in foldable relation there-

to, said member having a wall portion extending longitudinally of and overlying a longitudinally extending peripheral wall portion of said receptacle when the member and receptacle are folded together, said member also having an end wall portion projecting beyond the open end of said receptacle when the latter and said member are folded together, and a sleeve mounted in said last mentioned wall portion carrying a catch for releasably holding said receptacle and member 10 in folded relation. 5

18. A container comprising a receptacle open at one end, a member hinged adjacent the opposite end of said receptacle in foldable relation thereto, said member having a wall portion extending longitudinally of and overlying a longitudinally extending peripheral wall portion of said receptacle when the member and receptacle are folded together, said member also having an end wall portion projecting beyond the open end 20 of said receptacle when the latter and said member are folded together, said last mentioned wall portion having an open end, a sleeve mounted in said open end of the last mentioned wall portion and carrying a catch for releasably holding 25 said receptacle and member in folded relation, and a cap mounted on said last mentioned wall portion for closing the open end thereof. 30

19. A container comprising a receptacle open at one end, a member hinged adjacent the opposite end of said receptacle in foldable relation thereto, said member extending longitudinally of and overlying a longitudinally extending peripheral wall portion of said receptacle when the member and receptacle are folded together, said member 35 having a peripherally continuous wall portion extending a substantial distance beyond said open end from a point immediately adjacent thereto when said receptacle and a member are folded together, said last mentioned wall portion carrying a catch for releasably holding said receptacle and member in folded relation, and a finger piece 40 for operating said catch disposed on said last mentioned wall portion inwardly of the free end thereof. 45
